UNITED STATES PATENT OFFICE.

FORGUS O. GODMAN, OF FORT WAYNE, INDIANA, ASSIGNOR, BY DIRECT AND MESNE ASSIGNMENTS, OF THREE-FOURTHS TO CHARLES W. BEEKER, OF WEST LAFAYETTE, INDIANA.

CAR-BRAKE.

SPECIFICATION forming part of Letters Patent No. 615,353, dated December 6, 1898.

Application filed November 5, 1897. Serial No. 657,498. (No model.)

To all whom it may concern:

Be it known that I, FORGUS O. GODMAN, a citizen of the United States, residing at Fort Wayne, in the county of Allen and State of Indiana, have invented a new and useful Car-Brake, of which the following is a specification.

The invention relates to improvements in car-brakes.

10 The object of the present invention is to improve the construction of car-brakes and to provide a simple and comparatively inexpensive one which will be strong and durable and adapted for various street-railway cars and the like, such as electric and cable cars.

15 A further object of the invention is to provide a brake which when applied will be capable of instantly exerting great pressure on the wheels of a car; and another object of the invention is to enable the power of an electric car to be automatically shut off in applying the brake and the latter to be similarly thrown off the wheels in applying the power.

20 The invention consists in the construction and novel combination and arrangement of parts, as hereinafter fully described, illustrated in the accompanying drawings, and pointed out in the claims hereto appended.

25 In the drawings, Figure 1 is a side elevation, partly in section, of a portion of a car provided with a brake constructed in accordance with this invention. Fig. 2 is a plan view. Fig. 3 is an end elevation. Fig. 4 is a detail sectional view on line 4-4 of Fig. 3. Fig. 5 is an enlarged detail view illustrating 30 the manner of mounting the brake-shoes on the brake-levers. Fig. 6 is a detail view of one of the bearing-brackets. Fig. 7 is a detail view of one of the brake-shoes.

35 40 Like numerals of reference designate corresponding parts in all the figures of the drawings.

45 50 11 designate brake-levers, disposed in pairs at each end of the frame 2 of a car and fulcrumed at their outer ends on brackets 3, which are secured to the same at the corners thereof, as clearly illustrated in Figs. 2 and 3 of the accompanying drawings. The brackets 3, which depend from the frame 2, are provided with inwardly-extended perforated ears

4, between which the outer ends of the levers 1 are secured by vertical pivots 5.

The brake-levers, which are horizontal, carry brake-shoes 6, arranged near their outer ends in holders 7 and adjustably mounted on the brake-levers by means of clips 8 and wedges 9. The engaging face of the brake-shoe conforms to the configuration of the wheel 10, and the holder 7, which is bolted or otherwise secured to the clip 8, is provided with a dovetailed recess 11, receiving a dovetailed shank 12 of the brake-shoe, whereby the latter is detachably interlocked with the holder.

The holder 7 and the clip 8 are provided with suitable eyes to receive the connecting fastening device, and the holders 7 are held steady by a transverse connecting-bar 7^a, which is suitably secured at its ends to the holders. This connecting-bar 7^a, which 55 spaces the holders and maintains them in proper relation with each other, is centrally and forwardly bowed at 7^b for a purpose hereinafter described. The clip 8, which embraces the brake-lever, also receives the wedge 9, which is located at the inner edge of the brake-lever and which is adapted to be advanced into the clip as the brake-shoe becomes worn in order to take up the wear and enable the brake-shoe to engage the wheel properly. The adjustable wedge 9 is provided with a serrated or corrugated face to prevent it from slipping, and the upper and lower sides of the clip, which are provided with threaded portions, receive a connecting clip-plate 12^a and nuts 13, which are adjusted to permit the clip to be advanced by the wedge 9 to take up the wear. By locating the brake-shoes near the outer ends of the levers in the manner shown a powerful 65 leverage is obtained, the inner arm being preferably seven times the length of the outer one; but the proportion may be varied as desired to obtain the necessary application of power.

95 The inner ends of the brake-levers are overlapped and slotted, one of the members being preferably bifurcated to receive the other member, and the slots 14 receive a roller 15, which pivots a coupling 16 to the levers. The 100

coupling 16 is provided with a horizontal ear or portion which is connected with the roller and vertical ears which are pivotally connected to a central depending arm 17 of a 5 rock-shaft 18, adapted to be rotated to carry the brake-shoes into engagement with the car-wheels. The rock-shaft 18, which is disposed transversely of the car, is journaled in sectional bearings 19 of bearing-brackets 20, 10 which are secured to the ends of the frame 2, as clearly illustrated in Fig. 2 of the accompanying drawings.

Each of the rock-shafts of the car is provided at its ends with arms 21 and 22, extending upward and downward from the 15 frame 2. The upwardly-extending arm of each rock-shaft is connected with the depending arm of the other rock-shaft by a longitudinal rod 23, which is provided with a turn-buckle 24 to enable the brake connections to be readily adjusted, and the connecting-rods 23, which are located at opposite sides of the car, enable the brake mechanism at the ends thereof to be simultaneously applied 20 when the upwardly-extending arm of either rock-shaft is operated. The arms 17 and 21 are of different lengths to increase the pressure, which is further increased by the brake-operating mechanism.

30 The brake-shoes are normally held off the wheels by a coiled spring 25, disposed on a bolt or pin 26 and secured to the frame 2 of the car. The bolt or pin 26 has its outer end connected with the levers and its inner end is 35 guided in a perforation of a plate 27 on the end of the frame 2, as clearly illustrated in Fig. 4 of the accompanying drawings. The plate or piece 27, which is clamped on the frame 2 of the car, depends therefrom and 40 forms a guide for the bolt or pin 26. The centrally-bowed portion 7^b of the transverse connecting-bar 7^a extends around the inner side of the device for holding the brake-shoes normally off the wheels and enables the bolt 45 or pin 26 to have full play.

Each upwardly-extending lever-arm 21, which may be connected with an ordinary 50 brake staff or shaft, is designed when applied to electric cars to be connected by a chain 28 or other suitable flexible connection with a horizontal sleeve or windlass 29, which is mounted upon a horizontal shaft 30 and capable of a limited longitudinal reciprocation to couple and uncouple itself from a gear-wheel 31 of a rheostat 32. The gear-wheel 31, which is vertical, is arranged on the exterior of the rheostat and meshes with a horizontal gear-wheel 55 at the top thereof, the horizontal gear-wheel being connected with a shaft of the rheostat. 60 The chain 28 passes over a guide-pulley 23 and extends upward through an opening of the platform of the car, and the shaft 30 is journaled on the post 34 and the rheostat 32.

The sleeve or windlass 29, which has a hand-wheel 35 fixed to it, carries one member of a 65 clutch 36, the other member being carried by the gear-wheel 31. When the hand-wheel is

rotated, the sleeve or windlass is controlled by a key 37, consisting of an L-shaped arm secured to the top of the post 34, extending 70 over the sleeve or windlass and engaging a guide-groove of the same. The guide-groove is composed of parallel annular portions 38 and 39, which are connected by a switch portion 40, disposed at an angle to the plane of 75 the grooves 38 and 39 and extending from one to the other. The grooves 38 and 39 extend substantially around the sleeve or windlass, and when the key engages the groove 39 the sleeve or windlass is at the inward limit 80 of its longitudinal reciprocation and in position for winding the chain around it to apply the brake. In relieving the wheels of the 85 brake-shoes the wheel 35 is rotated sufficiently to carry the switch portion 40 of the guide-grooves to the key, and a continued rotation of the hand-wheel will effect an outward movement of the shaft or windlass and carry the clutch-section into engagement, thereby 90 coupling the hand-wheel to the rheostat. The groove 38 permits the hand-wheel to make nearly a complete revolution in manipulating the rheostat, which movement is amply sufficient for such purpose. In applying the 95 brake the hand-wheel is rotated in the direction for winding up the chain; but prior to the application of the brake the power of the motor is automatically shut off and the hand-wheel uncoupled from the rheostat.

The invention has the following advantages: The brake is simple, strong, and durable and adapted for applying sufficient pressure to the wheels of a car to effect a rapid stoppage of the same. The brake-shoes are 100 adjustably mounted on the brake-levers, and any wear on them may be readily taken up. The brake may be applied from either end of a car, and when it is applied the power of the 105 motor is automatically shut off prior to such application of the brake. The brake is thrown off the wheels before the power is applied to start the car. It is impossible to put the motor in operation while the brake is applied, and the brake cannot be set until the current is turned off.

110 Changes in the form, proportion, and minor details of construction may be resorted to without departing from the spirit or sacrificing any of the advantages of this invention.

115 What I claim is—

120 1. The combination of a frame or support, 125 brake-levers arranged in pairs at the ends of the frame or support, fulcrumed at their outer ends thereon and provided at points between their ends with brake-shoes, pivots passing through the inner ends of the levers, the pins guided on the frame or support and connected with the pivots, coiled springs disposed on the 130 said pins and interposed between the frame or support and the inner ends of the levers, transverse rock-shafts arranged at the ends of the frame or support at points above the 135 brake-levers and provided with depending centrally-arranged arms connected to the

outer ends of the said pins, said rock-shafts being provided at their ends with arms extending upward and downward from them, and connections between the end arms of the 5 rock-shaft, substantially as described.

2. The combination of a frame or support, a brake lever or bar, a clip embracing the brake lever or bar, a brake-shoe connected with the clip, and an adjustable wedge arm- 10 ranged within the clip and interposed between the same and brake bar or lever and adapted to advance the clip to take up wear on the brake-shoe, substantially as described.

3. The combination of a frame or support, 15 a brake lever or bar, a clip mounted on the brake lever or bar, a holder pivotally connected with the clip and provided with a dove-tailed recess, and a brake-shoe having a dove-tailed shank fitting in the recess, substan- 20 tially as described.

4. The combination of a frame or support, transverse brake-levers fulcrumed at their outer ends on the frame or support, a pivot passing through the inner ends of the levers, 25 brake-shoes mounted on the levers, a rock-shaft journaled on the frame or support and provided with a depending arm, a pin guided on the frame or support and connected with the pivot and with the arm of the rock-shaft, 30 and a coiled spring disposed on the pin and interposed between the frame or support and the inner ends of the levers, substantially as described.

5. The combination with a brake mechanism, of a rheostat having a horizontal gear-wheel at its top, a vertical gear-wheel arranged on the exterior of the rheostat and meshing with the horizontal gear-wheel, a horizontal windlass capable of reciprocation, a flexible 35 connection wound around the windlass and attached to the brake mechanism, a coupling for connecting the windlass with the vertical gear-wheel, and means for automatically reciprocating the windlass to couple and un- 40 couple it from the gear-wheel as it is rotated, 45 substantially as described.

6. The combination with a brake mechanism, of a rheostat provided with an exterior gear-wheel, a windlass located outside of the

rheostat, capable of reciprocation and pro- 50 vided with parallel guide-grooves having a connecting switch portion, a key engaging the grooves and adapted to cause a reciprocation of the shaft or windlass, and a coupling de- 55 vice composed of members carried respec- tively by the windlass and by the gear-wheel of the rheostat, substantially as described.

7. The combination with a brake mechanism, and a rheostat, of a horizontal reciprocating windlass connected with the brake 60 mechanism, arranged outside of the rheostat and provided with parallel annular grooves having a connecting switch portion, a fixed key engaging the grooves, a coupling com- 65 posed of two sections, one of the sections be- 70 ing connected with and carried by the wind- lass, and means for connecting the other sec- 75 tion with the rheostat, substantially as de- 80 scribed.

8. The combination with a brake mechan- 70 ism, of a rheostat having an exterior verti- cally-disposed gear-wheel, a reciprocating windlass provided with a hand-wheel for ro- 75 tating it, a flexible connection wound around the windlass and attached to the brake mech- 80 anism, a coupling for connecting the windlass with the gear-wheel, means for automatically reciprocating the windlass when the same is rotated, whereby the said windlass will be 85 coupled to the gear-wheel and uncoupled from the same, and a horizontal gear-wheel mesh- 90 ing with the vertical gear-wheel and connect- 95 ing the same with the rheostat, substantially as described.

9. The combination with a frame or sup- 85 port, of a brake bar or lever, a brake-shoe mounted on the brake bar or lever, and an adjustable wedge interposed between the 90 brake-shoe and the bar or lever and adapted to advance the brake-shoe as it becomes worn, substantially as described.

In testimony that I claim the foregoing as my own I have hereto affixed my signature in the presence of two witnesses.

FORGUS O. GODMAN.
